UNITED STATES PATENT OFFICE.

WILLIAM H. EGBERT, OF NEWARK, NEW JERSEY, ASSIGNEE TO THE
TURNBULL & COMPANY, OF SAME PLACE.

DESIGN FOR A HEARSE-BODY.

SPECIFICATION forming part of Design No. 25,180, dated February 18, 1896.

Application filed December 28, 1892. Serial No. 456,593. Term of patent 14 years.

To all whom it may concern:

Be it known that I, WILLIAM H. EGBERT, a citizen of the United States, residing at Newark, in the county of Essex and State of New Jersey, have invented a new and original Design for a Hearse-Body, of which the following is a specification.

The accompanying drawings represent, in Figure 1, a side view of my hearse - body. Fig. 2 is a partly sectional view showing the arrangement of the columns and frame.

This design relates to the ornamentation of hearse-bodies by means of columns disposed outside of the body, resting on the base of the body, the said columns standing out in relief from the frame and apparently, though not actually, supporting the roof of the hearse. This gives a new and distinctive appearance to the body of the hearse. In the drawings

the said columns are placed near the corners 20 of the hearse-body.

A is the frame of the hearse-body, B is the base, C C are the columns in relief, and D is the roof, the whole embodying the features of my design, which consists, essentially, of 25 the frame A, supported by the base B, and itself supporting the roof D, and the columns C resting on the base B and apparently supporting the roof D, the said columns being separate from the frame A. 30

What I claim is—

The design for a hearse-body, substantially as shown and described.

WILLIAM H. EGBERT.
